UNITED STATES PATENT OFFICE.

ALBERT J. DAVIES, OF KENOGAMI, QUEBEC, CANADA.

FOURDRINIER MACHINE.

1,196,845.

Specification of Letters Patent. Patented Sept. 5, 1916.

Application filed January 5, 1916. Serial No. 70,401.

To all whom it may concern:

Be it known that I, ALBERT J. DAVIES, of Kenogami, in the Province of Quebec, a citizen of the United States, and residing at the above place in the Dominion of Canada, have invented certain new and useful Improvements in Fourdrinier Machines, of which the following is a specification.

This invention relates to paper making machines of the Fourdrinier type and may be used as an addition to my U. S. Pat. No. 1,090,974, issued Mar. 24, 1914, where I provide mechanism to alternately reciprocate the vacuum or suction boxes, for the purposes therein set forth. I have found, in practice, that these opposing reciprocations admirably served the purpose for which they were intended for all but the final box of the series which, by reason of the fact that there was no opposing reciprocation ahead of it, had a tendency to carry the screen or apron with it and thus cause the grooving of the forward lip of the box, with the undesirable consequences, at that point, which were general at all the boxes before the time of my invention described in the above patent. To overcome this tendency, I have conceived this present invention which includes means for reciprocating the guide roll over which the screen passes in its course from the last suction box to the couch roll and, by causing this reciprocation to oppose that of the last box, I introduce conditions there that are similar to those at all the other boxes for, as is well known, the screen itself is given slight vibratory motions at the breast roll, for the purpose of "forming the sheet" and thus the first box is met with the desirable counter-agitation behind it that I here provide, in a different manner, ahead of the forward box.

In the drawings which accompany and form part of this specification, Figure 1 is a diagram of a portion of a Fourdrinier machine. Fig. 2 is a cross elevation, on line 2—2, of Fig. 1. Fig. 3 is a partial plan view of Fig. 2. Fig. 4 shows a modification.

In the description which follows, the reference characters will, in general, follow the order given in my previous patent above mentioned, so that reference may conveniently be had to that patent.

Thus,—2 represents the "shaker rail," 3 the "deckle strap," 4 the feed or guide roll to which my present invention is preferably

applied, 5, 5 the couch rolls, 6, 7, 8, 9, 10 and 11 the suction boxes, the first mentioned, 6, being nearest the roll 4. The shaking bars 12 and 13 are best seen in Fig. 2, the general mounting being the same as in my above mentioned patent, the pivotal bearings being indicated at 14, Fig. 1.

To reciprocate box 6, which is attached to the bars 12 at 16 (Fig. 3), the same eccentric 65 22, on shaft 23, has a rod 21 pivotally connected to the brace 18 at 20, this brace being fastened to the bars 12, as seen in Fig. 2. Hereafter, the additional reference characters refer exclusively to the accompanying 70 drawings.

Feed roll 4 is mounted at one end in a fixed bearing 25 on frame 1; the journal 26 being free to either turn or slide therein. At its opposite end, the journal 27 is rotatably mounted in a standard 28 but is held 75 against sliding therein by a collar 29 fast on journal 27.

Standard 28 is rigidly supported on a shelf 30 and this shelf is connected at 31 to 80 a stiff spring-plate 32 which is connected at 33 to a floor casting 34. A pivotal mounting 35, at one side of shelf 30, affords connection to an eccentric rod 36 and thence to the eccentric 37 on shaft 23. 85

The reciprocating movement of roll 4 need be but slight, in some cases less than one-sixteenth part of an inch, so the small yield of plate 32 will not appreciably affect the alinement of journals 26 and 27, and the 90 plate 32 may be sufficiently stiff to offer a satisfactory standard, being aided, in this respect, by the eccentric rod support.

The screen or apron 38, having the usual forward motion, is thus adversely affected 95 by box 6 and roll 4 and any tendency to "carry" on the former is broken up.

In Fig. 3 it will be noticed that box 7 is secured to shaking bar 13 at 17, this bar being reciprocated by its eccentric 22, similarly to bar 12 but in the opposite direction, so that the effect, on screen 38, by the movement of box 6, is broken up or opposed on each side by box 7 and roll 4. 100

Although I have, so far, treated and prefer to use this invention in connection with my previous Patent No. 1,090,974, it will be noticed that the sliding of roll 4, in conjunction with the usual "sheet-forming" movement of apron 38 at the breast end of the machine might, in some cases, suffice to obviate the necessity of shaking the suction boxes at 110

all; and this fact should be properly considered in limiting the scope of this invention. Furthermore, for the purposes of this invention, roll 4 need not revolve, the essential feature being a support for the apron at the couch end of the machine. A pulley 40, seen in Fig. 2, shows one means of transmitting power to shaft 23. The flexible suction tubes are seen at 41, Fig. 1.

10 In Fig. 4, the bearing 28^a receives journal 27^a both rotatably and slidably, being itself fixed to frame 1. An extension 50 of journal 27^a bears against a cam 51 fast on shaft 23, being held there by a spring 52 which impinges on bearing 28^a and a loose collar 53, the latter being held against a collar 54 fast on journal 27^a. I do not limit myself to the precise construction shown.

What I claim is:—

20 1. In a machine of the Fourdrinier type, an apron adapted to contact with suitable suction boxes; a support for said apron at the couch end of said machine and forward of said boxes; and means for transversely reciprocating said support to shake said apron from said couch end back over said boxes.

25 2. In a machine of the Fourdrinier type, an apron adapted to contact with suitable suction boxes; a roll mounted in guiding relation to said apron at the couch end of said

machine; and means for transversely reciprocating said roll to shake said apron from said couch end back over said boxes.

3. In a machine of the Fourdrinier type, 35 a plurality of suction boxes; an apron adapted to contact with said boxes; and means for transversely reciprocating said boxes; in combination with a support for said apron at the couch end of said machine 40 and forward of said boxes; and means for transversely reciprocating said support to shake said apron from said couch end back over said boxes.

4. A frame; a roll having journals at 45 both ends; a fixed bearing for one of said journals and adapted to slidably and rotatably receive the same, said bearing being fast on said frame; a journal box for the other of said journals and adapted to rotatably receive the same; means for preventing said other journal from sliding in said box; and a movable support for said box; in combination with means for transversely reciprocating said movable support to impart reciprocating motion to said roll. 50

In testimony whereof, I have affixed my signature in the presence of two witnesses.

ALBERT J. DAVIES.
